CLAIM

The ornamental design for a television receiver, as shown and described.

DESCRIPTION

The file of this patent contains at least one drawing/photograph executed in color. Copies of this patent with color drawing(s)/photograph(s) will be provided by the Office upon request and payment of the necessary fee.

1. Television receiver

1.1 : Perspective

1.2 : Front

1.3 : Back

1.4 : Left

1.5 : Right

1.6 : Top

1.7 : Bottom

1.8 : Enlarged

1.9 : Enlarged

The dash-dot broken lines of figures 1.1, 1.4, 1.8 and 1.9 are included to show partially enlarged views only and form no part of the claimed design.

(Continued)

The color shading shown in figure 1.9 is included for the purpose of illustrating unclaimed portions of the television receiver and forms no part of the claimed design.
